UNITED STATES PATENT OFFICE.

DANIEL J. SEIBERT, OF WINNIPEG, MANITOBA, CANADA.

REFRIGERATOR.

1,254,367.

Specification of Letters Patent. Patented Jan. 22, 1918.

Application filed December 4, 1916. Serial No. 134,992.

To all whom it may concern:

Be it known that I, DANIEL J. SEIBERT, of the city of Winnipeg, in the Province of Manitoba, Canada, have invented certain new and useful Improvements in Refrigerators, of which the following is the specification.

The invention relates to improvements in refrigerators of that class generally known as iceless refrigerators which are rendered cool by the evaporation of water and the object of the invention is to provide a refrigerator which is improved both in construction and operation.

With the above and other objects in view, which will be more apparent as the description proceeds, the invention consists essentially in a refrigerator box having a closed bottom, a door, a top pan compartment and an air pipe leading from the compartment, a plurality of air flues contained within the box, passing through the bottom of the refrigerator and communicating with the top compartment, said flues forming the bounding walls of the cooling chamber, a water pan in the top compartment, absorbent fabric lining the flues, strips of absorbent fabric leading from the pan to the interior of the flues and shelves contained within the box between the flues, the parts being arranged and constructed as herein-after more particularly described and later pointed out in the appended claims, reference being had to the accompanying drawings in which:—

Figure 1 represents a vertical sectional view through a refrigerator embodying my invention.

Fig. 2 represents a horizontal sectional view through my refrigerator.

Fig. 3 represents an enlarged detailed vertical sectional view through one of the flues showing the end receiving tubes and the feeding strips.

Fig. 4 represents a perspective view of a fragmentary portion of one of the flues.

Referring now to the drawings in which like characters of reference indicate corresponding parts in the several figures:—

1 represents a refrigerator box or outer casing of the usual form provided at the front with an entrance door 2 and supported on the corner legs 3' which are in the present instance actually extensions of the corner posts 3.

The box is provided with a closed bottom 4 and top 5 and is supplied with an internal horizontally disposed divisional plate 6 which forms with the top and side walls of the box, a compartment 7 in which I insert a water pan 8.

An air pipe 9 leads from the top of the pan compartment and in actual practice this pipe is connected with a chimney flue so that a good air draft can be had as later enlarged upon.

Within the box I locate two side flues 10 and 11 and a back flue 12 which are identical in construction and are of such a size that they in reality form the inner walls of the refrigerator or in other words inclose the cooling chamber.

Each flue is formed from a flattened metallic tube having the sides thereof pierced to provide a plurality of inwardly extending tongues or lips 13 which are adapted to obstruct the flow of air passing through the flues.

The inner faces of the flues are lined with an absorbent material indicated at 14 and 80 it will be noticed that the tongues are pierced through this material so that actually when one views the interior of the flues he sees the lining with the tongues projecting through.

With each flue I associate a pair of aligned upright top and bottom flat tubes 15 and 16, the tubes 15 in each instance being lined with absorbent material 17 and being permanently secured to the divisional plate 90 while the tubes 16 in each instance are permanently fastened to the bottom 4 of the box.

The flues are inserted in position within the box by first telescoping the upper ends 95 of the flues over the lower ends of the top pipes 15 which, it will be noticed, project below the divisional plate and then afterward inserting the lower ends of the flues into the upper ends of the bottom tubes and 100 dropping them until the side lugs 18 provided on the flues engage the upper ends of the latter tubes.

In this connection I wish it to be noted that sufficient clearance is provided at the lower ends of the upper tubes to allow the flues to be slipped up far enough to admit of the easy insertion or withdrawal of the lower end of the flues from the lower tubes.

With such provision made it is a very

easy matter to insert or remove the flues for cleaning or repair purposes.

The upper ends of the tubes 15 terminate above the top level of the pan 8 and they are provided on the pan side with cross slots 20 and with nipples or short tubes 21 which have their outer ends terminating adjoining the outer walls of the said tubes.

22 represents feeding strips of absorbent material having their inner ends immersed in the water 23 placed in the pan and their outer ends passed through the slots 20 turned downwardly and bearing against the absorbent lining 17 of the tubes on the side next 15 the pan.

24 represents feeding strips of absorbent material passed through the nipples and having their inner ends immersed in the water of the pan and their outer ends hanging down and bearing against the lining of the tubes remote from the pan.

With this arrangement it will be seen that the water in the pan is fed by capillary action by the strips 22 and 24 to the tube linings at both sides with the result that the tube linings are dampened as are also the linings of the flues.

Any dripping from the flues is passed down through the tubes 16 to the drip pan 30 25 located between the legs beneath the bottom of the box.

26, 27 and 28 represent refrigerator shelves inserted through the doorway into the cooling chamber 29 and carried by sets of corner brackets 26', 27' and 28' fastened securely to the corner posts and extending inwardly between the adjoining edges of the flues.

When this refrigerator is in use a strong air draft is effected through the flues, this draft entering the flues at the bottom, through the tubes 16 and escaping from the flues at the top through the tubes 15. Afterward it passes through the pipe 9 to the chimney flue. In passing upwardly through the flues the air draft is more or less arrested by the tongues and in its passage is cooled by the evaporating water. The result is that the edible material placed in the refrigerator on the shelves is kept at a comparatively low temperature so that it is properly preserved without the use of ice as ordinarily occurs.

I wish it to be particularly noticed in con-

nection with this invention that the absorbent material is on the inside of the flues 55 and that the air is circulated through the flues and further that the flues in themselves form the inner wall of the refrigerator, that is to say they form the sides of the cooling chamber.

What I claim as my invention is:

1. A refrigerator depending upon the principle of evaporation for the performance of its cooling function, comprising an outer casing having a closed top and bottom and interiorly divided to present a top pan compartment and a lower cooling chamber, an air pipe leading from the top compartment, a water pan within the top compartment, a plurality of aligned vertically disposed flat tubes located adjacent the inner walls of the casing and projecting through the bottom of the top compartment and the bottom of the casing, a plurality of upstanding fabric lined flues connecting the tubes 75 in pairs and inclosing the sides of the cooling chamber and strips of absorbent material immersed in the water of the pan and adapted to feed water by capillary action to the fabric lining of the flues. 80

2. A refrigerator depending upon the principle of evaporation for the performance of its cooling function, comprising an outer casing having a closed top and bottom and interiorly divided to present a top pan 85 compartment and a lower cooling chamber, an air pipe leading from the top compartment, a water pan within the top compartment, a plurality of aligned vertically disposed flat tubes located adjacent the inner 90 walls of the casing and projecting through the bottom of the top compartment and the bottom of the casing, a plurality of removable upstanding fabric lined flues telescoped on the tubes and inclosing the 95 sides of the cooling chamber and strips of absorbent material immersed in the water of the pan and adapted to feed water by capillary action to the fabric lining of the flues. 100

Signed at Winnipeg, this 10 day of November 1916.

DANIEL J. SEIBERT.

In the presence of—

G. S. ROXBURGH,
K. B. WAKEFIELD.
